United States Patent Office.

DAVID SANDERS, OF MILWAUKEE, WISCONSIN, ASSIGNOR TO HIMSELF
AND J. D. PIERCE, OF SAME PLACE.

Letters Patent No. 104,889, dated June 28, 1870.

STOVE-PIPE DAMPER.

The Schedule referred to in these Letters Patent and making part of the same.

I, DAVID SANDERS, of Milwaukee and county of Milwaukee, in the State of Wisconsin, have invented certain Improvements in Dampers, of which the following is a specification.

Nature and Object of the Invention.

The nature of my invention is to knock the soot on the damper as it is turned, and also to have the damper with cup swells on the sides.

Description of the Drawing forming part of this Specification.

Figure I is a plan view of my invention.
Figure II is a sectional view of same.

General Description.

A is the flat portion of the damper.
B, the handle and one of the gudgeons
C, the other gudgeon.

D, the holes through the flat portion of the damper.
E, the cups bolted onto the damper.
F, lugs on the flat portion of the damper, which the cups sit in between.

G, tongues in the cups.

As this damper revolves, the tongues strike the sides, and knock the soot from it.

Claims.

I claim as my invention—

1. A damper with flat, straight surface A, when made with holes D, cups E, and lugs F, substantially as described.

2. A damper, when made with holes D, cup E, and tongues G, substantially as described.

DAVID SANDERS.
